(57) **CLAIM**

The ornamental design for footwear outsole, as shown and described.

DESCRIPTION

FIG. 1 is a left perspective view of a footwear outsole showing my new design;

FIG. 2 is a left side elevational view thereof;

FIG. 3 is a right side elevational view thereof;

FIG. 4 is a front elevational view of the footwear outsole design of FIG. 1;

FIG. 5 is a rear elevational view of the footwear outsole design of FIG. 1;

FIG. 6 is a top plan view of the footwear outsole design of FIG. 1; and,

FIG. 7 is a bottom plan view of the footwear outsole design of FIG. 1.

The broken line showing a shoe upper throughout the views illustrates the portion of the design that forms no part of the claim.
